UNITED STATES PATENT OFFICE.

SALVADOR ANCIRA GARCIA, OF GUADALAJARA, MEXICO.

SAFETY-LOCK FOR DETECTING THE VIOLATION OF CONTAINERS.

1,323,527.

Specification of Letters Patent.

Patented Dec. 2, 1919.

Application filed March 22, 1919. Serial No. 284,500.

To all whom it may concern:

Be it known that I, SALVADOR ANCIRA GARCIA, a citizen of Mexico, and a resident of Guadalajara, State of Jalisco, Mexico, have invented certain new and useful Improvements in Safety-Locks for Detecting the Violation of Containers, of which the following is a specification.

My invention is an improvement in safety locks, and has for its object to provide a device of the character specified adapted for securing containers of every character in such manner that any attempt to gain access to the contents of the container will be indicated by the lock.

In the drawings:

Figure 1 is a perspective view of the improved lock;
Fig. 2 is a section on the line A—A of Fig. 1.

In the present embodiment of the invention the lock consists of two sections, one of which, in boxes, for instance, may be attached to the body of the box and the other to the cover, the said sections interlocking when pressed together to prevent entrance to the box without disclosing that it has been opened. That is, the arrangement is such that the lock must be destroyed or torn from the container to gain access to the interior thereof.

The improved lock consists of a section which is adapted for connection with one of the elements to be locked together, and a section adapted to be connected with the other element. The first named section, which is formed of sheet metal of proper weight, is doubled upon itself to form an upper flap A and a lower flap C, the said flaps extending at a very acute angle with respect to each other, and the uppermost flap A has spurs or lugs D extending downwardly past the edges of the flap C and adapted to pierce the container wall and to be clenched on the inner side of the wall to secure the sections A—C to the container.

The flap A has the free end thereof bent downwardly and inwardly to lie approximately parallel with the flap as indicated at B, and at the junction between the flap A and the flange B there is an opening E for a purpose to be presently described. The section G which is also of sheet metal has

spurs or lugs H which extend downwardly and are adapted to penetrate the material 55 of the container and to be clenched on the inner face thereof to secure the section to the container, and this section has a tongue F which is adapted to enter the slot E. This tongue F is reduced, being of less 60 width than the section G and formed by cutting away the edges of the section G at the tongue, and the tongue is provided at its free end with a lip I extending downwardly and backwardly at an acute angle 65 to the tongue.

This lip I, when the sections are locked together, is adapted to engage the flange B to prevent disengagement of the sections without destroying the lock or tearing the 70 same from the container. The lip I forms no impediment to the entrance of the tongue through the slot E, but absolutely prevents disengagement, since a movement of the section G away from the sections A—C will 75 result in the lip passing below the flange through the space between the flange and the flap C, and no manipulation of the section can possibly arrange the parts so that they may be detached.

While the device is mentioned in connection with boxes, it is obvious that it might be used with cords or ribbons, the sections being connected with the ends of the cords or ribbons and the said cords or ribbons 85 being adapted to pass around a box or the like. The fastener may be used with containers of paper, pasteboard, tin, glass or the like, and may be used for fastening paper bags or containers of any character 90 whatever.

I claim:

1. A lock of the character specified consisting of sections adapted for connection with the parts to be fastened together, one section 95 consisting of upper and lower flaps connected at one end, the upper flap having means for connecting the section to the container, and the free edge of the upper flap having an inwardly and downwardly extending flange provided with a slot at the junction of the flange with the flap, the other section having means for securing it to the container, and having a tongue adapted to enter the slot and provided with a 105 downwardly inclined lip for engaging the

flange to prevent disengagement of the sections.

2. A safety lock comprising sections adapted for connection with the parts to be fastened, one section having upper and lower walls and a downward and inwardly curved flange at one end of the up-

per wall, and having a slot at the junction of the flange with the section, the other section having a tongue for entering the flange and provided with a lip for engaging the flange to lock the parts together.

SALVADOR ANCIRA GARCIA.
